UNITED STATES PATENT OFFICE.

HENRY L. GATES, OF MILWAUKEE, WISCONSIN, ASSIGNOR TO THE UTILITY MANUFACTURING COMPANY, OF SAME PLACE.

FLANGING-MACHINE.

SPECIFICATION forming part of Letters Patent No. 545,791, dated September 3, 1895.

Application filed March 11, 1895. Serial No. 541,268. (No model.)

To all whom it may concern:

Be it known that I, HENRY L. GATES, a citizen of the United States, and a resident of Milwaukee, in the county of Milwaukee and 5 State of Wisconsin, have invented certain new and useful Improvements in Flanging-Machines; and I do hereby declare that the following is a full, clear, and exact description thereof.

- 10 My invention has for its object to provide a simple, economical, efficient, and durable machine especially adapted for turning flanges of more than ordinary width on sheet-metal vessel-bodies without fracturing the material from which such bodies are formed; and 15 it consists in certain peculiarities of construction and combination of parts hereinafter set forth with reference to the accompanying drawings and subsequently claimed.
- 20 In the drawings, Figure 1 represents a vertical transverse section of a flanging-machine constructed according to my invention and organized to flange but one end of a sheet-metal vessel-body at a time, the view being 25 taken for the most part on line 1 1 of the succeeding figure; Fig. 2, a plan view of that portion of said machine below the flanging-head; Fig. 3, an elevation of the same, partly broken away; Fig. 4, a sectional view of a machine 30 embodying certain necessary features of my invention and organized to flange both ends of a sheet-metal vessel-body at the same time. Fig. 5 represents a machine similar to the one shown by the first three figures, but including 35 a reciprocative disk having the function hereinafter specified; Fig. 6, a detail elevation, partly in section, illustrating the disk in connection with a stay-plate; and Fig. 7, an elevation illustrating said disk carried by a reciprocative rotary head.

Referring by letter to the drawings, A represents the base in any form of my machine, and when the latter is organized as shown in Figs. 1, 2 and 3 said base is provided with recesses for the engagement of dowels b, depending from interchangeable circular plates B C, hereinafter more particularly described.

With particular reference to Figs. 1, 2, and 3 of the drawings it will be seen that a pintle D may be screw-threaded or otherwise rigidly joined to the base A, and in the organization

of the machine as illustrated by said figures the pintle is engaged by meeting ends of segmental frame-sections E F, one of which is offset to overlap the other, and thereby form 55 a hinge-joint. Rods G, screw-seated in the frame-sections E F or otherwise joined thereto and surrounded by spiral springs H, pass up through meeting ends of other segmental frame-sections I J, lapped on each other to 60 form another hinge-joint. By means of nuts d, run on the rods G against the frame-sections I J, the tension of the springs H may be regulated, and it will be understood that said springs constitute yielding supports for said 65 frame-sections. The segmental frame-sections E J being in rod connection and the ones F I in like connection, the entire frame may be readily opened or closed, and a projection e on the section I is engaged by a pivotal hook f on section J to hold said frame in its closed position. All of the segmental frame-sections are 70 preferably of cast-iron, and the upper ones I J are shaped to form interior seats for corresponding sections K of a hardened steel ring, that 75 presents right-angle working faces preferably joined by a curve, and the ring-sections are held in place by the engagement of depending dowels g with corresponding recesses in the adjacent frame-sections. 80

The hardened steel ring constitutes a support and shaper for the flange to be turned on a sheet-metal vessel-body, the operation being effected by means of rollers L, loose on spindles M, that radiate from a rotative head 85 N and are preferably adjustable therein, as clearly shown in Fig. 1. It is also necessary in practice that the head N have movement longitudinally of its axis, in order that the rollers L may come on and off the opposing 90 end of a vessel-body inclosed within the above-described frame and ring. Therefore I show said head fast on a shaft P, that may be rotated by any suitable means and raised or lowered at the will of the operator, although 95 I have not deemed it necessary to illustrate any particular mechanism for accomplishing these results, because reciprocative rotary heads are common in various sheet-metal-working machines.

If the machine be organized as shown in Fig. 1, a vessel-body will be set in the frame

to encircle the stay-plate B and have its outer end flush with the upper face of the hardened steel ring above specified. Now, if the rotary head be lowered, the rollers L thereon, being of suitable working contour will first expand said end of the vessel-body against the adjacent curved inner edge of the hardened steel ring, after which, by continued downward movement of said head working in opposition to the yielding frame-sections I J, the expanded end of said vessel-body will be drawn horizontally between said rollers and ring to complete the flange, the width of the latter being proportionate to travel of the aforesaid head and yield of said frame-sections on their supporting-springs.

The flanging operation being completed, the head is lifted and the expansion of the springs H returns the frame-sections I J to normal position, lifting the flanged vessel-body therewith. After this operation it is not necessary to open the machine-frame to withdraw the vessel-body therefrom, as only one end has been flanged, and this end is outermost. Therefore it follows that it is not always essential that said frame be separable, as herein shown and described.

When one end of a vessel-body has been flanged and it is desirable to flange the other end, I employ the stay-plate C in place of the one B, the substitute plate being provided with a seat of suitable contour to receive the previously-formed flange and prevent the same from getting out of shape when the action of the head takes place in the manner above described. This organization of the machine is shown in Fig. 3, and it follows that there must be a separable frame in order to permit insertion and withdrawal of the vessel-body.

In Fig. 4 I show a machine organized to flange both ends of a vessel-body at the same time, there being a separable frame that has a stationary half mounted on the base A and a movable half in hinge connection with the one aforesaid. There are necessarily two sets of spring-controlled segmental frame-sections I J, and hardened steel ring-sections K, pertaining to these frame-sections, are held in their seats by screws h or other suitable means, the frame being horizontal instead of vertical. There being two hardened steel rings there are two reciprocal rotary heads N, carrying rollers L, and in practice said heads will be rotated in opposite directions. In this form of my machine the frame is opened to permit the insertion or withdrawal of a vessel-body, and one of the latter being positioned in said frame the heads are brought toward each other to turn flanges at both ends of said body at the same time.

In the latter form of machine the frame-sections E F are intermediate of the two sets of those I J, the first of the former sections being provided with feet i, bolted to the base. The pintle D and rods G extend through all the frame-sections, and said rods are held

against longitudinal play by means of collars j, abutting the frame-sections E F, the springs H being intermediate of these collars and those frame-sections that have loose play on the aforesaid rods.

The frame of the double-flanging machine may be held closed by the same means as above described in connection with those forms of my machine adapted for flanging but one end of a vessel-body at a time.

In Figs. 1, 2, and 3 I show that the stay-plates B C may be made in the form of rings or washers to save metal; but in Figs. 5 and 6 I show each plate solid throughout and provided with a central post Q, surrounded by a spiral spring R, and resting on this spring is a disk S, loosely arranged on the post within the vessel normally parallel to the hardened steel ring or flange-shaper K, above specified. The disk S is run down against resistance of spring R by the pressure of the flanging-rollers L and operates to prevent the vessel-body from buckling while an end flange is being turned. The flanging having been completed, the expansion of spring R operates to return the disk to normal position as the head N recedes.

In Fig. 7 I show that the disk S may be carried by the flanging-head if found more desirable; but in any case it is reciprocative and serves the purpose above explained. The disk will be found necessary in working light stock and may be used to advantage in any form of the machine.

Having thus described my invention, what I claim as new, and desire to secure by Letters Patent, is—

1. In a machine for flanging sheet-metal bodies, the combination of a suitable body-receiving frame having a yielding flange-shaping portion, a rotary head movable longitudinally of its axis, and flanging rollers carried by the head in opposition to said yielding portion of the frame.

2. In a machine for flanging sheet-metal bodies, the combination of a body-receiving frame having a yielding portion, a flange-shaper seated in the yielding portion of the frame, a rotary head movable longitudinally of its axis, and flanging rollers carried by the head in opposition to said flange-shaper.

3. In a machine for flanging sheet-metal bodies, the combination of a separable body-receiving frame having yielding portions, flange-shaper sections seated in the yielding portions of the frame, a rotary head movable longitudinally of its axis, and flanging rollers carried by the head in opposition to the flange-shaper.

4. In a machine for flanging sheet-metal bodies, the combination of a body-receiving frame having a yielding portion provided with a flange-shaper, a stay-plate on the machine-base within said frame, a rotary head movable longitudinally of its axis, and flanging-rollers carried by the head in opposition to the flange-shaper.

5. In a machine for flanging sheet-metal bodies, the combination of a separable body-receiving frame having yielding portions, a flange-shaper section seated in each yielding portion of the frame, a stay-plate on the machine-base within said frame, a rotary head movable longitudinally of its axis, and flanging rollers carried by the head in opposition to the flange-shaper.
10. In a machine for flanging sheet-metal bodies, the combination of a body-receiving frame comprising rods, springs surrounding the rods and a flange-shaper having its holder loose on the rods against the springs; a rotary head movable longitudinally of its axis, and flanging rollers carried by the head in opposition to the flange-shaper.
15. In a machine for flanging sheet-metal

bodies the combination of a suitable body-receiving frame having a yielding flange shaping portion, a rotary head movable longitudinally of its axis, flanging rollers carried by the head in opposition to said yielding portion of the frame, and a disk operative within a vessel-body in the machine to prevent buckling of this body while a flanging operation is taking place.

In testimony that I claim the foregoing I have hereunto set my hand, at Milwaukee, in the county of Milwaukee and State of Wisconsin, in the presence of two witnesses.

HENRY L. GATES.
